UNITED STATES PATENT OFFICE.

ALVIN A. FRANCIS, OF MARCUS, WASHINGTON, ASSIGNOR OF ONE-THIRD TO SAUL S. ZWANG AND ONE-THIRD TO DANIEL W. WILBUR, BOTH OF MARCUS, WASHINGTON.

SHIPPING-CRATE.

1,322,419.

Specification of Letters Patent.

Patented Nov. 18, 1919.

Application filed August 23, 1918. Serial No. 251,142.

To all whom it may concern:

Be it known that I, ALVIN A. FRANCIS, a citizen of the United States, residing at Marcus, in the county of Stevens, State of Washington, have invented certain new and useful Improvements in Shipping-Crates; and I do hereby declare the following to be a full, clear, and exact description of the invention, such as will enable others skilled in the art to which it appertains to make and use the same.

This invention relates to folding crates and it has for its object to provide a construction wherein there may be employed reinforcing plates against which the sides and ends will stand when the crate is set up so as to prevent them from swinging outwardly and the upstanding portions of which plates will be incased when the crate is folded and thus be protected from injury.

A further object of the invention is to provide a simple means for pivotally and slidably connecting the cover in a durable manner and with economy.

The inventive idea involved is capable of receiving a variety of mechanical expressions one of which, for the purpose of illustrating the invention, is shown in the accompanying drawings wherein:

Figure 1 is a perspective view of the crate in its operative or unfolded position.

Fig. 2 is a central longitudinal section therethrough looking toward the front of the crate.

Fig. 3 is a similar view looking at the back thereof.

Fig. 4 is a central transverse section.

Fig. 5 is a perspective view of the crate in its folded or inoperative position.

Fig. 6 is a longitudinal section therethrough when folded.

Fig. 7 is a transverse section.

Fig. 8 is a section on the line 8—8 of Fig. 3.

The crate is shown in the accompanying drawings in what is now believed to be its preferred form and the same may be made of any desirable material and comprises a solid bottom of rectangular or oblong rectangular formation and including the central member 10 having the front and back upstanding strips 11 and 12, secured against its front and back edges, respectively, with the back strip being of a greater height than the front strip. The bottom further

includes the upstanding end strips 13 secured against the end edges of the member 10, all of said strips being braced at their meeting ends by the angular reinforcing plates 14 secured to the strips with suitable fasteners and having the portions 15 projecting above the upper edges of the strips.

Hinged at 16 to the front strip 11, to fold from erect position to lie upon the member 10, is the front 17 of the crate which includes a frame 18 having a plurality of slats or bars 19 secured thereto. When in erect position, the front is held against outward and downward movement by engagement with the portions 15 of the reinforcing plates 14. When folded the ends of the front 17, as best shown in Fig. 6, will rest upon the upper edges of the end strips 13 of the bottom, which are of the same height as the front strip 11, and the outer surface of the front 17 will be in a plane below the upper edge of the back strip 12, which is correspondingly higher than the end and front strips.

The crate further comprises the ends 20 each of which consists of a frame 21 having the slats or bars 22 secured thereto. Each end 20 has its forward vertical edge portion disposed against the rear face of the frame 85 of the front member and connected thereto by hinges 33 so as to fold against the inner face of the front member. When unfolded, the outward movements of the ends are limited by engagement with portions 15 of the 90 reinforcing plates 14, so as to stand upon the end strips 13. When the front member 17 is folded inwardly and downwardly, its ends lie upon the end strips 13 of the bottom while the end members lie within the 95 inclosure of all of the strips. This is for the reason that when unfolded, the end members have their front vertical edges against the frame of the front member and in consequence, when folded inwardly against the 100 front member, they swing from over the end strips. The ends 20 are each provided with a handle 24 preferably formed of rope whereby the handling of the crate may be facilitated when the same is in its operative 105 or unfolded position.

A back 25 for the crate is constructed in the same manner as the front 17 and is hinged to the back strip 12 at 26 and stands upon the upper edge of said strip when the 110

back is in its unfolded position, said hinges permitting of the folding of the back member onto the front 17, as shown in Figs. 6 and 7. To hold the end members to the 5 back member when the crate is unfolded or set up, hooks 29 are pivoted against the inner faces of the end members in position to engage their bills in recesses 27 behind the latch plates 28 that are secured against the inner faces of the end portions of the 10 back member. The upper edge of the back 25 is provided with a longitudinally extending groove 30 in which is embedded a pivot and guide rod 31 the ends of which project from the ends of the back as 15 shown. The rod 31 is held in its position along the edge of the back by means of cleats 33 secured to the back and engaging over the rod.

20 The crate is completed by a top 34 having the depending end flanges 35 and the front flange 36, the former being provided throughout the major portion of their lengths with the longitudinally extending 25 slots 37 which receive the projecting ends of the rod 31 whereby to both pivotally and slidably support the top upon the back. The end and front flanges 35 and 36 are braced by the reinforcing plates 38 at the 30 corners of the top. When the top is in its closed and operative position, the ends of the rod 31 are at the rear ends of the slots 37 and in order to adjust the top to its folded or inoperative position the same 35 is first swung about the ends of said rod as a pivot to a substantially vertical position in a plane of said back 25 whereupon the top may be lowered. In order to aid in guiding the top while being lowered the 40 inner surfaces of the end flanges 35 have secured along the lower edges thereof the guide bars or strips 39, the rear ends of which terminate short of the back and said bars form grooves which receive the ends 45 of the back. It will be understood of course that the top need not be adjusted as just described when it is only desired to open the crate to obtain access to the interior thereof. Such adjustment of the top 50 however is the first step made when it is

desired to fold the crate to the position shown in Fig. 5.

A lock is provided for the top and consists of a staple 40 secured to the front 17 and engageable by the hinged section 41 of 55 the hasp 42 secured to the front flange 36 of the top. In order to lock the crate in its folded or inoperative position, the front strip 11 of the bottom is also provided with a staple 43 which is likewise engageable by 60 the section 41 of the hasp, as clearly shown in Fig. 5 and in each instance, it will be understood that any form of lock may be engaged with the staples to maintain the 65 top in its closed position. To facilitate the handling of the crate when the same is in its folded position, the end strips 13 of the bottom 10 are provided with handles 44 similar to the handles 24.

70 It will be noted that as before stated, the angular brace plates 15 extend above the strips 11 and 13. When the crate is set up, inward bending of the projecting edges of these plates is of course prevented. When the crate is folded, these projecting 75 edge portions 15 are received within the enclosure of the depending flanges of the top and are thus protected against injury.

What is claimed is:—

80 A folding crate comprising a bottom, a front, end and back members arranged to fold over the bottom, the back member having a groove formed longitudinally of its upper edge, a rod fixed in the groove and projecting at both ends from the back member, and a top having depending end flanges having longitudinal slots and inwardly directed strips below the slots and terminating short of the rear end of the top, the 85 slots receiving the ends of the rod pivotally and slidably for movement of the top to receive the back member between its body portion and said strips.

90 In testimony whereof, I affix my signature, in the presence of two witnesses.

ALVIN A. FRANCIS.
